UNITED STATES PATENT OFFICE.

OWEN J. McGANN, OF PITTSBURG, PENNSYLVANIA.

GAS PRESSURE-REGULATOR AND CUT-OFF.

SPECIFICATION forming part of Letters Patent No. 374,485, dated December 6, 1897.

Application filed January 7, 1897. Serial No. 223,709. (No model.)

To all whom it may concern:

Be it known that I, OWEN J. McGANN, a citizen of the United States, residing at Pittsburg, in the county of Allegheny and State of Pennsylvania, have invented certain new and useful Improvements in Gas Pressure-Regulators and Cut-Offs; and I do hereby declare the following to be a full, clear, and exact description of the invention, reference being had to the accompanying drawings, which form part of this specification.

My invention has relation to gas pressure-regulators and cut-offs, and relates particularly to certain improvements on the pressure-regulator and cut-off for which Letters Patent were granted to me December 21, 1886, No. 354,719.

In the said Letters Patent I have described and shown a tubular double-acting supply-valve having two seating portions and ports or openings through the shell of the tubular body between the said seating portions, the said valve being connected to and its movement regulated and governed by a diaphragm arranged in a chamber on the low-pressure side of the valve, the two seating portions of the valve and seats for the same being so arranged that they might seat separately but not simultaneously.

In the said Letters Patent I have also shown and described the tubular valve as having a prolongation of its body below the lower seating portion, which fitted and worked within a chamber formed in the bottom of the valve-casing, the object of such arrangement being to present as little surface as possible to the pressure of the gas on the high-pressure side of the valve.

In practice I have found certain difficulties in the construction of the tubular valve; and the present invention has for its object the provision of means for dispensing with the tubular portion of the valve and the ports leading thereto, and in the provision of means for producing an absolute balancing of the valve under any and all conditions and variations of pressure.

In the described patented device I have also found it necessary (in order to obviate the necessity of finishing the prolongations of the tubular valve and the chamber in which it

worked so accurately as to absolutely prevent leakage into the space below) to provide a packing-ring through which the prolongations of the tubular valve might work.

My present invention has for its further object the provision of means for dispensing with the necessity of either accurately fitting these parts or providing a packing therefor.

Having in view the accomplishment of the above objects, my invention consists in the novel construction, arrangement, and combination of parts and devices, hereinafter described and claimed, and more particularly in the novel construction of the valve body or stem, which I propose to provide with external ways or by-pass grooves or spaces, in lieu of the hollow cylindrical body and the ports through the walls of the same; in the provision of a peculiarly-arranged diaphragm which is arranged in the space or chamber in which the prolongations of the valve-body work, and is secured at its center to the bottom of the prolongations of the valve-body and at its edge to the valve-casing, the object of said diaphragm being to prevent the access of gas to the bottom of the prolongation of the valve-body, and in the novel construction of the valve-body and its casing and the other parts of the device, as will hereinafter more fully appear.

Referring now to the accompanying drawings, Figure 1 is a vertical sectional view of my improved apparatus, and Fig. 2 a detail view of the valve.

A designates the pressure-reducing chamber, containing the diaphragm B, through the medium of which the supply-valve is governed and operated. Said chamber is composed of two similar or nearly similar sections provided with annular flanges through which pass fastening-bolts, and said diaphragm, which is composed of any suitable flexible body, has its edge held securely between said flanges. A disk or plate, C, rests upon top of the diaphragm B, and upon top of said plate is a post or upright, C', that fits nicely and works in a neck, C", in the top of the diaphragm-chamber. Below the diaphragm is a hollow depending stem, D, having a shoulder, d, between which and the diaphragm is placed a washer, d'. The upper end of the stem D passes through the diaphragm and the plate

C and screws into a screw-threaded cavity, c, in the post C'. Ports c' c' lead out from the cavity c to the space above the diaphragm, and similar ports, c² c², lead from the interior of the hollow depending stem D to the space below the diaphragm. The uppermost end of the stem D is formed with a valve-seat, d², upon which seats a valve, d³, opening upwardly and held down by a spring, d⁵.

At D' the stem D is pivoted to a weighted lever, F, and below said pivotal point the stem fits into and works in a socket, e, which is in alignment with the neck C², thus giving the stem D and the upright C', which form 15 practically a continuous piece, a bearing at each end, so that there can be no sidewise movement of the same.

F designates a lever pivoted, as before mentioned, at D' to the depending stem D and on 20 a pivot or fulcrum, G. This lever F rests and works in a cavity, h, formed in the bottom of the diaphragm-chamber, so as to leave free space for the movement of the said lever.

H designates the valve-casing, secured to a 25 flange, g, formed on the lower part of the diaphragm-chamber, by a flange, h', and bolts h² h². This valve-casing receives the inlet-pipe I and outlet-pipe J, and contains the chamber K, divided into high and low pressure compartments by a partition, L. Passing through 30 the partition L and projecting through into the high and low pressure compartments of the valve-casing is a cylindrical tubular section or pipe, M, made either integral with the partition L, as shown in the drawings, or 35 screwing thereinto, as desired. This pipe M serves both as a guide and seat for the valve, and is formed with a seat, m, at its upper end and a seat, m', at its lower end.

Below the tubular section or pipe M a wide neck, N, is formed in the casing, and in said neck is placed a bush, n, having a lateral flange, n', at its end. The interior diameter of the bush n corresponds to the interior diameter of 45 the pipe or tube M, and serves as a receptacle and guide for a portion of the valve-body, as will presently appear.

O designates the valve-stem, which is pivotally connected to the lever F, and at its lower 50 end has a shoulder, o, and a screw, o', that screws into a triangular or other angularly-shaped solid section, O', which fits and slides within the tubular portion or pipe M.

In the drawings I have illustrated the section O' as being triangular in cross-section; but I wish it to be understood that I do not confine myself to this configuration, as the said section may be square, septagonal, octagonal, or any other desired configuration such 55 as will allow of a bearing within the pipe M, and at the same time will allow the passage of gas through the said pipe. A plate, o², and a rubber or other flexible washer, o³, are placed between the shoulder o and the section O', and 60 the said plate and washer constitute the upper seating portion of the valve, resting, when the

valve is down, upon the upper end of the pipe M. The lower end of the section O' is formed with a screw, o⁴, which screws into a solid cylindrical section, O², which forms a prolongation of the valve-body. A washer, o⁵, and plate o⁶ are fixed between the sections O' O² and constitute the lower seating portion of 70

the valve, resting, when the valve is raised, against the bottom of the tube M. The plate o² and the washer o⁵ are at such distance from the plate o⁴ and washer o⁶ that, while either of them may be separately seated, they cannot be seated simultaneously, and when both are off their seats the gas from inlet-pipe I has a free 80 passage between the flat sides of the section O' and the inner wall of the pipe M. The lower section, O², of the valve fits in the bush n, and to the end of said section is secured a cap or cup, P, of rubber or other suitable material, by 85 means of a metal plate, p, and a screw, p', passing up into the bottom of the section. The cup P has a lateral annular flange, P', that extends out under the flange of the bush n, and the lower edge of the interior of said 90 bush is hollowed out, as at n², to give room for the spreading of the cup, which issues from the depression of the valve. A head, R, having a lateral flange, r, and a central concavity, r', is placed over the cup P, and bolts s serve 95 to secure the bush, the cup, and the head to the neck N, passing through the flanges on the end of same. A small pipe, S, leads from the space between the head R and the cup P to the escape-pipe S', which opens into the 100 space above the diaphragm in the diaphragm-chamber, and at its other end leads into the open air.

T designates a small pipe having a small valve and a minute valve-opening, said valve 105 being opened by a push-button, t, and closed by a spring. This pipe T leads from a point on the high-pressure side of the valve to a point in the diaphragm-chamber beneath the diaphragm, and its object is to supply sufficient gas to gradually elevate the diaphragm, and thereby open the valve after the same has been positively closed by the cessation of the flow of gas; and its further object is to detect leakage, as will be hereinafter described. 115

Operation: The several parts being constructed and arranged as described and shown and the valve being in the condition illustrated—that is, with the gas flowing from the inlet-pipe I through the pipe M and into the 120 diaphragm-chamber and the outlet-pipe J—so long as the pressure remains constant the valve will remain stationary. Upon any increase of pressure the diaphragm will rise, thereby lowering the valve, and by this movement causing the washer o² to approach more closely to the seat on top of pipe M and diminishing the flow of gas. Upon any decrease of pressure the valve is raised and the space between the washer o² and the seat on top of pipe 125 M is increased. Should the flow of gas entirely cease, the diaphragm, sinking, will raise 130

the valve until the lower washer, o^2 , comes into positive contact with the lower end of the pipe M. The flow of gas will be thus entirely cut off until the apparatus is again set in motion, which may be accomplished as soon as the gas begins to flow in the main by pressing the button t, and thereby opening the little valve in the pipe T and allowing gas to gradually enter beneath the diaphragm from the high-pressure side of the valve. The gas so entering raises the diaphragm, the valve is again opened, and the apparatus operates as before. Through the medium of this small valve and the pipe T it may be readily determined whether any gas is leaking at any point on the low-pressure side of the valve or from any of the pipes, joints, or cocks connected therewith, for if there be any such leakage the gas passing through the very small opening in the small valve will not accumulate sufficient pressure to raise the diaphragm, and hence so long as the leakage exists the valve will not again commence operations. If, for any reason, the valve should fail to operate so as to maintain a properly-reduced pressure in the diaphragm-chamber or the service-pipes, dangerous accidents will be averted by the escape of gas through the safety-valve in the stem of the diaphragm, and thence to the open air through the pipe S'.

I consider the most important feature of my present invention to be the means for absolutely balancing the valve, and this is accomplished as follows: The valve, when in its open position or in its closed position, presents as a surface upon which the pressure of the gas can be exerted to interfere with the movement of the valve only the underneath side of the lower seating portion, and as the area of such portion is very small, being only so much as is outside of the edge of the cylindrical section O^2 , the amount of force required to overcome such pressure is but small. As it is desirable, however, to have the valve move with absolute freedom, I have compensated for the pressure on the bottom of the lower seating portion by the employment of the elastic cup P, which presents a surface equal to the surface of the exposed portion of the lower seating portion, and as the pressure is exerted downwardly on said cup by the gas which passes down around the lower section, O^2 , of

the valve, which fits somewhat loosely in the bush n, the upward pressure on the lower seating portion is compensated for and the valve thereby balanced. Thus it will be seen I have devised a perfectly-balanced valve wherein but a single portion of the valve is seated at one time. The cup P serves, also, in addition to balancing the valve, as a spring or cushion and prevents sudden fluctuations or fluttering of the valve.

The manner of constructing the solid portion of the valve between the seating portions—that is, of an angular form—renders it easy to fit such portion in the tubular section M and obviates the laborious and expensive fitting which is required when said portion is cylindrical and hollow.

Having fully described my invention, I claim—

1. In a gas pressure-regulator and cut-off, the combination, with a double-acting valve having two seating portions at such distance apart relatively to their seats as to allow them to close separately, but not simultaneously, and having the portion between the seating portions angular in cross-section, of a tube or pipe the ends of which serve as seats for the said seating portions, and which embraces the body of the valve between its seating portions, serving to guide the same while allowing of the passage of gas, substantially as described.

2. In a gas pressure-regulator and cut-off, the combination, with a valve-chamber communicating with a high-pressure pipe and a low-pressure pipe, and a double-acting valve interposed between the high and low pressure compartments of said chamber, and having two seating portions, and connected to an operating-diaphragm situated above the upper seat, and a cylindrical prolongation below its lower seating portion, of an elastic cup secured to the said cylindrical portion and having its edges fixed to the valve-casing, substantially as described.

In testimony that I claim the foregoing I have hereunto set my hand this 6th day of January, 1887.

OWEN J. McGANN.
